Primary Examiner — Jennifer Rivard*Assistant Examiner* — April Rivas(74) *Attorney, Agent, or Firm* — Skaar Ulbrich Macari, P.A.**CLAIM**

We claim an ornamental design for a memory heat dissipation sink, as shown and described.

DESCRIPTION

FIG. 1 is a front perspective view of a memory heat dissipation sink showing the claimed design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view illustrating the details of the dot-dash area "9" shown in FIG. 1; and,

FIG. 10 is an enlarged view illustrating the details of the dot-dash area "10" shown in FIG. 1.

The dashed broken lines in the figures represent portions of the article which form no part of the claimed design.

The dot-dash lines in the figures represent the boundaries of the enlarged areas which form no part of the claimed design.
